INVENTOR,

PETER ANDERSON.

BY HIS ATTORNEYS.

James T. Williamson

UNITED STATES PATENT OFFICE.

PETER ANDERSON, OF OWATONNA, MINNESOTA.

PENCIL PIN AND CLIP.

Application filed October 4, 1920. Serial No. 414,545.

To all whom it may concern:

Be it known that I, PETER ANDERSON, a subject of the King of Sweden, residing at Owatonna, in the county of Steele and State 5 of Minnesota, have invented certain new and useful Improvements in Pencil Pins and Clips; and I do hereby declare the following to be a full, clear, and exact description of the invention, such as will enable others 10 skilled in the art to which it appertains to make and use the same.

My invention has for its object to provide an extremely simple and highly efficient pencil pin and clip which may be 15 attached to a piece of clothing by a single downward and inward movement of the hand holding the pencil.

To this end, it consists of the novel devices and combinations of devices herein 20 after described and defined in the claim.

The invention is illustrated in the accompanying drawings wherein like characters refer to like parts throughout the several views.

25 Referring to the drawings:

Fig. 1 is a view in front elevation of my device mounted on a fragmentary portion of a pencil;

30 Fig. 2 is a vertical section on the line 2—2 of Fig. 1, showing in dotted lines my sticking member in engageable position;

Fig. 3 is a view in rear elevation showing my device pinned to and carried by a fragment of clothing.

35 The numeral 4 indicates an ordinary lead pencil on which my device is mounted. My pencil pin and clip is preferably folded from one strip of metal. A gripping band 5 encircles the pencil and is varied in form to 40 suit various types of pencils.

Spring fulcrumed on 5 is an elongated sticking member 6, pointed at one end 7 to pierce a piece of clothing. This member 6 is normally held in towards the pencil by 45 the bend 8. A bend at the top of the member 6 forms a lever head 9 against which force may be applied to pry out the sticking point 7, as shown in Fig. 2 by the dotted

lines. When the force is released, the sticking member springs back to its normal position. 50

It is found that a small rivet, bolt or other means of fastening 10 applied to the two sections of the folded lever head just above the fulcrum point assists the spring action 55 and keeps the device bent properly. However, this is not required.

Fig. 3 shows a portion of a pencil carrying my device fastened to a fragment of clothing 11. 60

Operation.

To secure my device to a piece of clothing, the pencil 4 carrying the combined pin and clip is pressed inward and downward with the hand, the sticking member 6 facing the clothing. This motion actuates the lever head, prys out the sticking point and inserts the same in the clothing. When the pencil is released, the sticking member springs 70 back into normal position clipping the pencil to the pinned clothing to prevent it from falling off. 65

It is to be understood that my device is capable of considerable variation in form 75 without departing from the spirit of the invention.

What I claim is:—

A pencil pin and clip bent from a single piece of metal, comprising a gripping band so encircling a pencil, an elongated sticking member bent from and spring fulcrumed on the said gripping band, operative when pried out to pin the pencil to a piece of clothing and when released to clip the pencil 85 to the pinned clothing, a lever head formed by the bend on the upper end of the said sticking member above the fulcrum, operative to spring the sticking member out when force is applied against the said lever head, 90 and means of fastening the folded parts of the said lever head together near the fulcrum point.

In testimony whereof I affix my signature.

PETER ANDERSON.
